UNITED STATES PATENT OFFICE.

HERBERT J. BLOCKI, OF SHEBOYGAN, WISCONSIN.

PACKING PAD.

Application filed February 11, 1924. Serial No. 691,961.

This invention relates to improvements in packing pads such as are used in packing eggs and dishes, and in wrapping furniture and the like for shipment. Such pads as have heretofore been used for this purpose have commonly been made to comprise a thin sheet of excelsior or other loose fibrous material bound by a retaining wall of paper or the like comprising a flattened hoop encircling the excelsior and open at its ends. As is well known, excelsior has a tendency to crumble, and where such pads as those above described are used the packing rooms are filled with dust, litter, and debris emanating from the open ends of the pad. To construct the wrapping sheets in the form of closed envelopes to be sealed at the ends, whereby to completely enclose the excelsior in each pad, would be an unwarranted expense in view of the price at which the market demands these articles.

It is the object of this invention to provide means for preventing the escape of litter and scrap material from the ends of such pads without going to the expense of providing sealing flaps for the ends of the pad wrapper. More particularly stated, it is my object to provide a method for eliminating the nuisance above referred to by a bulk treatment of entire bundles of pads so that no manipulation of individual pads will be necessary to accomplish the desired purpose.

By the new and improved method herein disclosed, it is my purpose to provide bundles of pads which will be more easily handled than has heretofore been possible, and individual pads, which, although preferably treated in the bundle, will have their respective ends sealed against the loss of dust and litter.

In the drawings:

Figure 1 is a plan view of a bundle of pads embodying this invention.

Figure 2 is a side elevation of the bundle contained in Figure 1.

Figure 3 is an enlarged detail view in perspective of a fragment of a single pad embodying this invention.

Figure 4 is a diagrammatic illustration of a bundle of pads being dipped in a vat of melted coating material.

Like parts are identified by the same reference characters throughout the several views.

The bundle as illustrated in Figures 1, 2, and 4 comprises a number of individual

pads 10 which are bound together in superposed relation by means of the cords 11. Each of such pads includes a paper wrapper 12 which is in the form of a flattened tube 60 and encloses a distributed mass or sheet 13 of excelsior or similar material. As is clearly shown in Figure 3, the wrapper 12 is open at its ends and exposes the filling of the pad. Through the open ends of such pads the 65 objectionable litter and dust above referred to have heretofore made their escape.

For the purpose of avoiding such litter, I provide a pan or vat 14 which is heated in any desired manner as by being placed 70 upon a heated surface 15, such as the top of a coal, oil, or electric stove. In this vat I place a quantity of some substance which is solid at normal atmospheric conditions but can be liquefied by the application of 75 heat or otherwise. I prefer that this substance when liquefied shall be adhesive and I find that waxes and paraffins of various commercial types are particularly satisfactory for the purposes of this invention. By 80 way of exemplifying such substances I will hereinafter refer only to paraffin which is preferred for the practice of this invention.

Sufficient paraffin will be placed in pan 14 so that when the paraffin is melted it will 85 fill the pan to the desired depth. For a pad of ordinary size a depth of one inch of paraffin will be adequate, although more or less may be used as desired. It is my purpose to accomplish the desired result of sealing the ends of the several pads without unnecessarily wasting the paraffin indicated at 16 in pan 14.

When the paraffin is liquefied, bundles of pads 10 have their respective ends dipped 90 momentarily into the body of paraffin indicated at 16. They need be allowed to remain with their ends dipped in paraffin only for the time necessary for the paraffin to penetrate the pad to the desired depth, and, if 100 the filler 13 is excelsior, penetration will occur almost instantly. When one end of the bundle has been dipped the bundle is suspended momentarily above the vat to permit any surplus of paraffin to drain therefrom and is then inverted and the other end is dipped.

When the dipping operation is completed the bundles and individual pads will appear as represented in Figures 1 to 3. The ends of the paper wrapping 12 of each pad will be slightly discolored as at 17, due to the im-

pregnation or coating of the paper with paraffin. The excelsior disclosed at the end of the pad at 18 will also be discolored, and each individual fiber of the mass will be 5
coated and will be connected to those fibers with which it contacts by a thin film of the coating material. There is no attempt made to provide a solid sheet of paraffin across the end of the pad and none is necessary. 10
This thin film of paraffin, by means of which the individual fibers of the excelsior are caused to adhere each to the other, effectively seals the end of the pad without destroying its resilience. In practice, very little 15
matter falls from the end of a pad which has been so treated, and the features which have been referred to above and have heretofore been regarded as very objectionable in pads of this character, are practically 20
eliminated.

In wrapping a piece of furniture the operator will take a bundle of pads and will first cut the cords 11 which bind the individual pads together in the bundle. He will 25
wrap the individual pads about the different portions of the furniture which are to be protected, and in so doing, must move, with the bundle, about the piece of furniture upon which he is working. I have found that 30
where pads are treated in the bundle by the method previously disclosed herein, their wrappers 12 become slightly adherent so that even though the cords 11 are removed there is nevertheless a tendency for the 35
bundle to retain its form. This result facilitates the work of the user of the pads, since in moving about the piece of furniture upon which he is working he can more readily move the bundle from place to place than 40
would be possible if the individual pads were loose and separated. The pads have little body in themselves, and consequently, are hard to handle unless retained together in some manner. In the practice of the 45
present invention the pads adhere just sufficiently to preserve the form of the bundle when the strings 11 are cut, but each individual pad can be removed from the bundle by a very slight pull thereon. This is obviously 50
true in view of the fact that the pads are adherent only adjacent their respective ends.

I have found that pads impregnated or coated at their ends with paraffin after the disclosure herein are particularly valuable 55
for packing small machinery and the like, in which the dust and litter from the old style of pad has heretofore caused much annoyance. These pads, however, may be used wherever such pads have heretofore been 60
employed, since the paraffining operation does not materially destroy the resilience of the individual pad and is in every way an improvement. I wish furthermore to make 65
it clear that I do not desire to limit my invention to the use of any particular filling 18, nor to the use of any particular wrapping material 12, nor to any particular coating material 16. It will be 70
obvious that many different materials can be used for each of these several functions and, even though there be no necessity for dipping the pad to keep its contents from 75
escaping from its ends, the dipping operation will nevertheless prove useful to retain together the several pads of a bundle after the manner heretofore described.

Furthermore, I recognize that the fibers comprising the excelsior mat may be treated by spraying instead of dipping to render 80
them mutually adhesive.

I claim as my invention:

1. As a new article of manufacture, a bundle of packing pads of the character described, each of said pads having open 85
ends and being disposed with its open ends in alignment with other pads of the bundle, and each of such ends of said pads being adherent to the ends of adjacent pads, whereby said bundle will retain its form 90
without securing cords.

2. A bundle of pads of the character described, said bundle comprising a superimposed series of individual pads having open ended wrappers and fibrous fillers, with the 95
open ends of the wrappers of the several pads in alignment, the ends of said pads at one end of the bundle being thinly coated with a waxy material, whereby the individual pads are mutually adherent and have 100
their ends substantially sealed against the loss of the filling material.

HERBERT J. BLOCKI.
